UNITED STATES PATENT OFFICE

2,269,156

LEAD-IN SEAL

August J. Kling, Schenectady, N. Y., assignor to
 General Electric Company, a corporation of
 New York

Application April 26, 1940, Serial No. 331,792

10 Claims. (Cl. 250—27.5)

This invention relates to seals having means to carry current through the walls of vitreous vessels, such for example, as cathode ray tubes, and has for an object to provide an improved type of seal for carrying current through the vitreous walls of a sealed vessel where a compact structure which imposes minimum strain on the wall is necessary.

It is also an object of my invention to provide an improved seal whose terminals are closely adjacent the walls of the vessel whereby the vessel may be passed through or remain in spaces not substantially larger than the vessel without the terminals.

It is a further object of my invention to provide special terminals for such a seal, which are capable of withstanding considerable mechanical strain imposed by connections made thereto with minimum danger of breaking the vitreous walls.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing in which Figs. 1 and 2, respectively, are cross-sectional side and end views of a portion of a cylindrical vitreous vessel embodying my invention, and Figs. 3, 4, 5 and 6, respectively, represent somewhat different modifications of my invention.

Fig. 1 illustrates a portion of a tubular vitreous vessel 10, which may, for example, be made of glass or quartz, having a ribbon 11 of metal foil passing therethrough at one point. The ends of the foil, which suitably consists of platinum, are bent over to lie contiguous with the wall of the vessel. This foil must have a thickness considerably less than one mil and is preferably about fifteen-hundredths to twenty-hundredths of a mil thick. The use of a conductor with such limited transverse dimensions is desirable to avoid any strain on the wall 10 through which the foil 11 is sealed.

The process by which this foil 11 is sealed through the wall 10 comprises first, melting a hole through the wall 10 sufficiently large to allow the foil 11 to pass therethrough and, second, resealing the wall 10, with or without additional vitreous material, around the foil 11 to restore the original uniform shape of the wall. After the ribbon 11 has been sealed within the wall, the externally accessible ends thereof are pressed

down flush with the wall to occupy a minimum amount of space.

Since the ribbon foil 11 has slight mechanical strength, a coating 12 of a conducting material, such, for example, as a point containing a metal, is applied over the portion of the foil 11 externally accessible and lying contiguous to the wall. This coating 12 is adapted to provide mechanical protection for the foil while at the same time being capable of conducting current thereto.

Conducting coatings, such as described above, are well known and may, for example, comprise a mixture of oil solvent, low melting point glass, and metal powder. After being painted in place, such paints are baked on and the solvent is burned away to leave a vitreous mass, which is nevertheless conducting since it is impregnated with metal. Metals suitable for mixture in such paints are gold, silver, platinum, and the like.

Certain types of such conducting paints have no glass therein and include essential oils and chlorides of the metal desired. During firing, the oils burn away and a very hard, bright coating of the metal remains, which is burned into the vitreous material on which it is fired. Such latter coatings are much lighter than those containing glass.

Fig. 2 is a cross-sectional view taken through the plane of the foil 11 in the wall 10. In this view the width of the foil 11 may be clearly seen. Inspection of Figs. 1 and 2 shows that a seal of the nature described herein is highly advantageous where a sealed cylindrical vessel, such as the vessel 10, must be passed through restricted spaces, as through holes within magnetic coils or the like. At the same time, the seal provides a mechanically rugged and reliable means for carrying current through the wall of a sealed vitreous vessel.

In Fig. 3, a modification of the above-described seal is shown wherein, in addition to the single foil 11, which is embedded partially within the wall 10, there is supplied an additional foil 13 of similar form. The hole melted through the wall 10 must be sufficiently big to accommodate both the ribbons 11 and 13, spaced apart a small distance. In resealing the hole, vitreous material is added not only around and between the ribbons 11 and 13, but is also added on the exterior of the wall 10, so that the surface of the wall is caused locally to assume the shape of a knob 14. The knob 14 is not, however, made sufficiently large to cover the projecting end portions 15 and 16 of the ribbons 11 and 13. A coating 17 of conducting material is applied over the knob 14 and

in contact with both of the projecting ends 15 and 16.

This form of seal is especially useful where it is desired to use spring clips, or the like, either temporarily or permanently, for each external connection to the seal. The vitreous walls and the knob are under minimum internal strain and are accordingly strong and rugged. A conducting path extends from such a spring clip to the conducting coating 17, to the projecting end portions 15 and 16, and thence through the ribbons 11 and 13 to the interior of the glass tube 10.

In Fig. 4, there is illustrated a partially completed seal in which six portions of foil 18, 19, 20, 21, 22, 23 are provided. As illustrated, the upper heavy lined portions are seen on the surface of the wall and the light lined portions are seen through the vitreous material of the wall. In making such a seal a relatively large hole is melted in the wall 10 and the six above-mentioned portions of foil are placed therethrough. Subsequently, additional vitreous material is melted into the hole around and between the foil portions 18-23 to restore the original shape of the wall 10. A coating of conducting paint, such as illustrated in Fig. 1, may then be applied over either or both sides of the wall 10 to make connection with and protect mechanically the portions of foil unembedded in the wall.

The structure as illustrated in Figs. 3 and 4, of course, provides for greater current-carrying capacity than where a single portion of foil is utilized, as in the structure of Fig. 1. There is, however, an important additional advantage in that, if one of the portions of foil is injured during the process of forming the seal, the other portions of foil maintain a conductive connection through the wall.

The aforementioned embodiments of my invention have been described as utilized in vessels formed of glass, quartz, or the like. In glass vessels it is highly desirable to use platinum or rhodium foil of the above-specified thickness. In quartz vessels it is desirable to use foil formed of iridium. In any specific case, where the vessel be formed of glass, quartz, or other materials, it is necessary that a conducting foil be used which will neither oxidize nor melt at the melting temperature of the material of the vessel. Such foil materials are herein termed "refractory."

Fig. 5 illustrates a structure in which it is desirable to make a seal having substantial mechanical strength for mounting elements on the interior of a vitreous vessel. In this modification a portion 24 of foil is welded or otherwise fastened to a small, relatively heavy piece of metal 25. The foil 24 and piece of metal 25 are sealed through the glass wall 10 so that the foil projects on the exterior and the piece of metal 25 on the interior. A coating of vitreous conducting paint 26 may be spread over the unembedded portion of the foil 24 to form the exterior connection. The piece of metal 25 is embedded in the wall 10 only enough to form an internal connection with considerable mechanical strength. The walls of the vessel are under no substantial internal strain and the seal is correspondingly rugged.

A small portion 27 of foil welded to a piece of metal 28 is sealed through the opposite side of the wall 10 in the same way as foil 24 and piece of metal 25. An incandescent filament 29 is then conductively fastened between the pieces of metal 25 and 28 which, since they are embedded in the

glass wall 10, afford the filament 29 ample mechanical support.

As illustrated, the foil 27 at the exterior of the glass tube 10 may make connection with a coating of conducting material on a glass knob 30, similar to the knob 14 and coating 17 illustrated in Fig. 3. Of course, if desired, a flush seal may be utilized on both sides of the tube 10 in Fig. 5.

Fig. 6 illustrates a very convenient means of providing a seal for carrying current to a metal disk 32, which is sealed in the glass tube 10 so as to close the passage therethrough except for a small aperture 33 in the center of the disk 32. In this embodiment a seal of the form illustrated by Fig. 1 may prove useful, if it be desired to provide a structure suitable for use in small space, since the ribbon foil 11 and the conducting coating 12 do not project substantially on the exterior of the tube 10. The interior pressed-down projecting end of the foil 11 is covered with a coating 34 of conducting paint, which also extends for a small distance on the wall 10 and upon disk 32 to make a conductive connection thereto. Current may therefore flow from the disk 32 through the coating 34 and ribbon foil 11, and through the coating 12 to any desired connecting means.

While I have shown particular embodiments of my invention, it will, of course, be understood that I do not wish to be limited thereto, since different modifications may be made both in the instrumentalities employed and in the arrangement thereof, and I aim by the appended claims to cover any such modifications as fall within the true spirit and scope of my invention.

What I claim as new and desire to secure by Letters Patent of the United States is:

1. In combination with a wall of vitreous material, means for conducting current therethrough comprising a refractory metal foil embedded in said wall, said foil having an externally accessible portion following the contour of said wall and lying contiguous thereto, a vitreous projection formed integrally with said wall and adjacent said externally accessible portion, said projection being shaped to facilitate making a mechanical connection thereto, and a coating of conducting material over said projection and said externally accessible portion providing mechanical protection for said foil, whereby there is a conducting path from said foil through the coating on said projection.

2. In combination with a wall of vitreous material, means for conducting current therethrough comprising a conductor embedded in said wall having an externally accessible portion following the contour of said wall and lying contiguous thereto, said conductor having a transverse dimension so small as not to impose appreciable strain on the vitreous material by its presence therein, a vitreous projection formed integrally with said wall and partially covering the externally accessible portion of said conductor, said projection being shaped to facilitate making a mechanical connection thereto, a coating of conducting material over said projection and said externally accessible portion providing mechanical protection for said conductor, said current conducting means providing a conducting path through said conductor and through said coating.

3. In combination with a wall of vitreous material, means for conducting current therethrough comprising a metal foil embedded in said wall, said foil having an externally acces-

sible portion following the contour of said wall and lying contiguous thereto, said foil being of limited thickness so as not to impose appreciable strain on the vitreous material by its presence therein, a vitreous projection formed integrally with said wall and partially covering said externally accessible portion, said projection having an enlarged end portion and a reduced shank portion shaped to facilitate making mechanical connection thereto, and a coating of conducting material over the uncovered part of said foil and over said projection to provide mechanical protection for said foil, said current conducting means providing a conducting path through said foil and said coating.

4. In combination with a wall of vitreous material, means for conducting current therethrough comprising a metal foil embedded in said wall, said metal foil having an externally accessible portion following the contour of the wall and lying contiguous thereto, said foil being of limited thickness so as not to impose appreciable strain on the vitreous material by its presence therein, a vitreous projection formed integrally with said wall and partially covering said externally accessible portion, said projection being shaped to facilitate making mechanical connection thereto, a coating of conducting material over said projection and said externally accessible portion to provide mechanical protection for said foil, means on the opposite side of said wall from said projection for performing an electrical function, and an electrical connection between said last means and said foil, said foil and said connection forming a conducting path through said wall between said means and said coating.

5. In combination with a hollow vessel having opposed walls of vitreous material, means for conducting current through one of said opposed walls comprising a metal foil embedded in said wall, said metal foil having an externally accessible end portion following the contour of the outer surface of said wall and lying contiguous thereto, said foil being of limited thickness so as not to impose appreciable strain on the vitreous material by its presence therein, a vitreous projection formed integrally with said wall and adjacent said externally accessible portion, said projection being shaped to facilitate making mechanical connection thereto, a coating of conducting material over said projection and over said adjacent externally accessible portion to provide mechanical protection therefor, an electrical device supported between said walls 55

and conductively connected to the other end portion of said metal foil, whereby an electrical path exists from said coating through said foil to said electrical device.

5. In combination with a body of vitreous material, means for conducting current therethrough comprising a conductor embedded therein, said conductor having an externally accessible portion following the contour of the adjacent surface of said body and lying contiguous thereto, a vitreous projection integral with said body adjacent said externally accessible portion, said projection being shaped to facilitate making a mechanical connection thereto, and a coating of conducting material over said projection and said externally accessible portion providing mechanical protection for said conductor, whereby a conducting path is formed from said conductor through said coating to the mechanical connection upon said projection.

10 6. In combination with a body of vitreous material, means for conducting current therethrough comprising a conductor embedded therein, said conductor having an externally accessible portion following the contour of the adjacent surface of said body and lying contiguous thereto, and a vitreous projection integral with said body adjacent said externally accessible portion, said projection being of knob-like form, thereby to facilitate the mechanical attachment of a terminal clip to said body and to hold the terminal clip in a position adjacent said body and said conductor.

15 7. In combination with a body of vitreous material, means for conducting current therethrough comprising a conductor embedded therein, said conductor having an externally accessible portion following the contour of the adjacent surface of said body and lying contiguous thereto, and a vitreous projection integral with said body adjacent said externally accessible portion, said projection being of knob-like form, thereby to facilitate the mechanical attachment of a terminal clip to said body and to hold the terminal clip in a position adjacent said body and said conductor.

20 8. An electron discharge device comprising an envelope of insulating material, a hole in the wall of the envelope, metallic means contiguous with the side of said hole having portions following contiguously the external contour of the surfaces of said wall adjacent said hole, and a plug sealed gas-tight in said hole.

25 9. A lead-in connection through a wall of insulating material, comprising a hole through the wall, a conductor through the hole contiguous with a side thereof and following contiguously the external contour of the wall adjacent the hole, and a mass of sealing material fixed in gas-tight union with the sides of the hole.

30 10. A lead-in connection through a wall of insulating material, comprising a hole through the wall, conducting means on the opposite exposed surfaces of the wall and on a side of said hole, such means being disposed in continuous conductive relation, and means hermetically sealing said hole.

AUGUST J. KLING.
